UNITED STATES PATENT OFFICE.

JOHN GEORGE LYDECKER, OF NEW YORK, N. Y., ASSIGNOR, BY MESNE ASSIGNMENTS,
OF ONE-HALF TO EDGAR M. GOLDSMITH, OF NEW YORK, N. Y.

AMUSEMENT DEVICE.

Application filed December 12, 1923. Serial No. 680,137.

To all whom it may concern:

Be it known that I, JOHN GEORGE LYDECKER, a citizen of the United States, and residing at 37 West 83rd Street, New York 5 city, New York, have invented new and useful Improvements in Amusement Devices, of which the following is a specification.

My invention relates generally to amusement devices and has particular reference 10 to a type of swing which is suspended from a carriage running on toothed tracks, supported on a suitable frame.

The principal purpose of the present invention is to provide a plurality of swings 15 of this character arranged in parallel sets of tracks, such swings being provided with means for advancing them by the motion of the swings themselves. It is intended that competitive races between the swings may 20 be afforded by the use of the particular mechanism employed to advance each swing independently of the adjacent swing or swings and that the rate of speed attained will depend entirely upon the skill of those 25 operating the swing.

A further object of the invention is to provide means for reversing the direction 30 of travel of the swings when the latter have been advanced to the ends of the toothed tracks.

The objects of the invention have been attained by the mechanism illustratively exemplified in the accompanying drawing, wherein Figure 1 is a perspective view of 35 my improved amusement device having two swings; Figure 2 is a perspective view of the carriage supporting the swing at one end, and the means for causing the swing to advance in either one direction or the other; Figure 3 is a plan view of the swing advancing mechanism; and Figure 4 is a side 40 elevational view of the same.

Referring to the drawings, 10 denotes the inverted V-shaped uprights, arranged at the 45 four corners of a supporting frame, and 11 designates the cross bars attached at opposite ends to the peaks of the two uprights at the ends of the device. Disposed longitudinally of the frame and arranged in pairs are two sets of angle iron pieces 12, which are secured at their ends to the uprights 10, as shown particularly in Figure 1. The inside pieces 12 of each pair are arranged closely adjacent and parallel to each other, and they are secured or sus-

pended from the cross bars 11 midway thereof. The uprights 10 are supported in upright positions by means of adjustable tie rods 13 which are provided with hooks at opposite ends to be received by suitable 60 eyes arranged in the uprights and ground or base, respectively.

The laterally extending portions of the angle pieces 12 of each pair are disposed towards each other and a toothed rack 14 65 is mounted on each lateral portion, as clearly shown in Figures 3 and 4. The carriages, which are movable over these racks 14, are identical in construction, so I shall describe in detail only one such carriage. 70

The carriage comprises a pair of angle plates 15 having their upright walls projecting upwardly from the lateral edges of the angle pieces 12 and their lateral portions projecting underneath and parallel to the 75 pieces 12. It will be apparent then that the upright walls of these members 15 are directed towards each other. The upright walls are connected together to provide a carriage by means of a shaft 16 disposed 80 transversely of the tracks. The opposite ends of the shaft 16 projects through the upright walls and receive toothed wheels 17, which mesh with and are supported by the toothed racks 14, as illustrated clearly 85 in Figures 2 and 3. In order not to permit the angle plates 15 to move out of parallel position with respect to the tracks, the lateral flanges thereof are provided with stop pins 18, adjustably mounted and 90 adapted to be brought into close proximity to the under surface of the angle bar 12 over which it advances. The angle plates operating on the inside track are provided with a pair of pivoted dogs 19 which are 95 substantially L shaped and pivoted to the plates at their upper ends. The lower arms of the dogs 19 project parallel to the shaft 16 and rest in opposite inclined positions upon the teeth of the rack 14, as shown in 100 Figures 2 and 4, so as to cause the edges of the arms to engage the teeth.

Disposed between the opposite upright walls of the members 15 and adjacent thereto are two swing supporting plates 20 provided with sleeves 21, which loosely embrace the shaft 16. The plates 20 are spaced apart by a sleeve 22 disposed about the shaft 16 and having its ends abutting the faces of the plates themselves. The plate 20 110

which is arranged beneath the angle plate 15, having the dogs 19, is provided with a hinged member 23 comprising a plate bent at a slight angle from the line of the hinge. 5 The position of member 23 is parallel to the swing supporting plate 20, and when one or the other side thereof is swung outwardly from the plate 20, the respective side will move in a path having a curve which 10 abuts the lower arm of the dog 19 and causes it to be moved upwardly and out of engagement with the teeth of the rack 14. The swings 24 comprise a body portion in which seats 25 are hung on U-shaped 15 hangers 26, the latter being pivoted in the side walls of the body or car, as shown in Figure 1. The cars are supported by means of depending rods 26 attached at their upper ends to the plates 20 and at their opposite ends to the upper edge of the car and at the four corners thereof.

When the carriages are at the starting end of the frame indicated A, and the operator wishes to permit the swing to begin 20 its advance, a cam 27 is operated against the adjacent wing of the pivoted member 23, so as to cause the latter to move until the other wing swings beneath the dog 19 which is disposed in the direction in which 25 the car and carriage are to travel. This cam 27 is fixed on a shaft 28 mounted transversely in the frame and parallel to and beneath the cross bars 11. It will be understood that a similar cam will be provided 30 for each carriage and that all cams will be mounted on the shaft 28. The outer end of the shaft 28 projects beyond the upright 35 10 and receives a lever 29 to effect the operation. A suitable spring arrangement 40 may be provided to cause the cam shaft 28 to normally hold the cam out of the path of the plate or pivoted member 23. At the opposite end of the course and carried by the frame is a reversing device comprising 45 plates 30, disposed at an angle to the tracks and adapted to receive the inwardly turned wing of the pivoted member 23, and to cause it to swing outwardly while the other wing moves beneath the dog directed in the return 50 direction.

In operation the competitive swings are filled with passengers and the cam 27 is operated to enable the cars to move away from the starting point A. The occupants impart the swinging motion to the cars and the latter swing in pendulum fashion until a height is reached which causes the hinged member 23 to engage and lift the dogs 19, whereupon the momentum of the load in 55 the car will cause the carriage to advance until the dog 19 is lowered and engages the teeth of its rack 14. The dog 19 directed in the direction opposite to that of the movement of the car will merely rest in the teeth 60 65 as the car advances and prevent the carriage

from advancing in a reverse direction. The rate of speed at which the swings advance will depend entirely upon the height the swings attain during the operation; if the movement of a swing is too vigorous, the carriage will tip and the stop pins engage into the tracks and no advance movement will be effected, while if the swing does not attain a certain height, the dogs 19 will not be lifted by the members 23 and no advance 70 movement will be made. When the swings finally reach one end of the frame the plates 20 will reverse the hinged member 23, and the dog 19, towards the starting end A, will be the one to be lifted and enable the swing to advance in a homeward direction, the swing first reaching the starting point naturally being the winner of the race.

What I claim is:

1. The combination of a toothed track, a carriage adapted to operate over said track, a swing supported by said carriage, means for advancing said carriage in a step by step movement over said track, and means disposed at opposite ends of the track for reversing the direction of movement of said carriage.

2. The combination of a toothed track, a carriage adapted to operate over said track, a swing supported by said carriage, and means for advancing said carriage in a step by step movement over said track, said means comprise a pair of pivoted members to engage the teeth of the rack in opposite directions, and means carried by the swing to engage the members and to lift them out of engagement with the rack, when the swing swings to a certain height, substantially as described.

3. The combination of a toothed track, a carriage adapted to operate over said track, a swing supported by said carriage, and means for advancing said carriage in a step by step movement over said track, said means comprise a pair of oppositely pivoted members to engage the teeth of said rack, and a hinged member carried by the said swing and adapted to be adjusted to engage one or the other of said pivoted members to disengage the latter from the track whereby the carriage may advance over the track, substantially as described.

4. An amusement device, as claimed in claim 3, in which the first named means comprise a pair of oppositely pivoted members to engage the teeth of said rack, a hinged member carried by the said swing to engage the one or the other of said pivoted members, and in which the last named means comprise a cam at the starting end of said track to engage the hinged member to reverse its position, and a fixed member at the opposite end of said track to be engaged by the hinged member to reverse its position, substantially as described.

5. The combination of a toothed track, a carriage adapted to operate over said track, a swing supported by said carriage, and means for advancing said carriage in a step by step movement over said track, said carriage comprising a pair of upright angle plates embracing said tracks and having a shaft connected at its ends to the plates, a toothed wheel fixed on opposite ends of the shaft and engaged with the racks, pivoted dogs on opposite sides of one of said wheels and adapted to engage the teeth of said rack in opposite directions, and means for lifting either one or the other of said dogs in the direction in which the carriage is to advance, substantially as described. 10
6. The combination of a plurality of parallel toothed tracks, a carriage adapted to support a swing running upon each pair of tracks, means carried by the carriages to engage the teeth of said tracks, means carried by the swings to engage the first named means to disengage the latter from the track when the swings are operated to a certain height, and means for engaging the second named means to cause the carriage to be advanced in a reverse direction. 15
7. The combination, as claimed in claim 8, in which said swings comprise cars having upright side walls, supporting members pivoted at opposite ends in said side walls, and seats carried by said members and adapted to swing relatively of said car to cause the latter to operate. 20
- In testimony whereof, I have signed my name to this specification. 25

JOHN GEORGE LYDECKER.
